(57) **CLAIM**

The ornamental design for a chair, as shown and described.

DESCRIPTION

- 1.1: a perspective view of the chair.
  - 1.2: a front elevational view thereof.
  - 1.3: a back elevational view thereof.
  - 1.4: a top plan view thereof.
  - 1.5: a bottom plan view thereof.
  - 1.6: a right side elevational view thereof.
  - 1.7: a cross-sectional view taken along line A-A of Figure 1.2.
  - 1.8: an enlarged end view along lines B-B, C-C of Figure 1.6.
  - 1.9: an enlarged view of Portion D-F of Figure 1.7.
  - 1.10: an enlarged view of Portion E-F of Figure 1.7.
  - 1.11: an enlarged view of Portion G-G of Figure 1.8.
  - 1.12: an enlarged view of Portion H-H of Figure 1.8.
- A left side elevational view of the chair is omitted because it is a mirror image of the right side elevational view; the parallel thin lines on the surfaces of the chair represent only shading and do not illustrate ornamentation or decoration; the thin lines on the surface of the chair are ridgelines to specify the shape of the solid surfaces; and the parallel lines on the sectional surfaces represent only hatching.
